(57) **CLAIM**

The ornamental design for a wrist rest for a rotary abrading tool, as shown and described.

DESCRIPTION

FIG. 1 is a perspective view of a wrist rest for a rotary abrading tool shown in a position of use;

FIG. 2 is a perspective view of the wrist rest for a rotary abrading tool;

FIG. 3 is a top plan view of the wrist rest for a rotary abrading tool;

FIG. 4 is a bottom plan view of the wrist rest for a rotary abrading tool;

FIG. 5 is a left elevational view of the wrist rest for a rotary abrading tool;

FIG. 6 is a right elevational view of the wrist rest for a rotary abrading tool;

FIG. 7 is a back elevational view of the wrist rest for a rotary abrading tool; and,

FIG. 8 is a front elevational view of the wrist rest for a rotary abrading tool.

The logo displayed on the wrist rest for a rotary abrading tool is a trademark owned by Dynabrade, Inc. The structure in broken lines in FIG. 1 represents the wrist rest for a rotary abrading tool in a condition of use and forms no part of the claimed design. The broken lines in the drawing in FIG. 4 show unclaimed portions of the design. The broken lines on the wrist rest in FIGS. 1, 2, 3, 5, and 6 represent unclaimed environmental material.
